UNITED STATES PATENT OFFICE.

HARRY G. WEBSTER, OF CHICAGO, ILLINOIS, ASSIGNOR TO MILO G. KELLOGG, OF CHICAGO, ILLINOIS.

COMBINED TELEPHONE-EXCHANGE AND ALARM SYSTEM.

No. 825,626.

Specification of Letters Patent.

Patented July 10, 1906.

Application filed October 10, 1904. Serial No. 227,876.

To all whom it may concern:

Be it known that I, HARRY G. WEBSTER, a citizen of the United States, and a resident of Chicago, county of Cook, and State of Illinois, have invented certain new and useful Improvements in a Combined Telephone-Exchange and Alarm System, of which the following is a full, clear, concise, and exact description, reference being had to the accompanying drawings, forming part of this specification.

My invention relates to systems in which line-circuits extending from subscribers' stations to a telephone-exchange and adapted for interconnection therewith are utilized for the transmission of special, fire, burglar, and other alarm signals in addition to their ordinary telephonic use.

The object of my invention is to provide an improvement upon a system proposed heretofore in which the line-circuit is at all times available for the transmission of an alarm signal and in which the alarm-sending and alarm-receiving apparatus does not cause any interference with telephonic signaling or conversation except upon the sending of an alarm signal, when the telephonic requirements may be disregarded. In such a system it is desirable that any accidental derangement of either limb of the telephone-line be automatically indicated at the alarm-receiving station, and it is also of advantage to maintain the alarm service by means of one limb only of the telephone-line in case the other limb be accidentally broken. It is also desirable that the electrostatic balance of the line be preserved without the use of artificial resistance and that the alarm mechanism be of simple and reliable character.

The improvement of my present invention consists in novel means for meeting these requirements, and it is in this respect a species under the generic invention set forth in the above application.

Other advantages of my improved system will be apparent to those skilled in the art from the following description.

In accordance with my invention I associate with the telephone-line a grounded source of current and an electromagnet having two opposing windings of equal energizing capacity, one winding being in circuit with each line-limb, respectively. The circuit of these windings is normally closed through a

high resistance or impedance in bridge of the two limbs, having a ground connection at a point intermediate of the two limbs, and the inductance of the path from either line-limb to ground through this bridge connection is substantially the same. As long as the line-limbs remain intact the flow of current through one winding of the magnet will be somewhat greater than that through the other, and the magnet will therefore be energized to a limited extent. In case the telephone is in use the flow of current through the two windings will be increased, but their relative energizing effect will still remain unequal, and in case that line-limb connected with the active or "live" side of the battery be connected directly to ground a relatively strong current will flow through one winding only, energizing the magnet to its greatest extent. Alarm-sending mechanism is provided of the nature of the ordinary "make-and-break" wheel of the district telegraph-box or of other construction, so arranged as to make and break a circuit of the line-limbs or the earth connection in a predetermined manner, and thus intermittently deenergize the electromagnet, which by its armature and contacts controls an alarm-indicating device in a local circuit. In a preferred form when energized to its greatest extent the electromagnet controls associated mechanism adapted to cause the display of a special signal to indicate the accidental grounding of the circuit. Also in its preferred form my invention contemplates a line-circuit in which the source of current is grounded at its center point and in which the bridged impedance, while having substantially the same inductance between its grounded center and each line-limb, is of greater ohmic resistance in one side than in the other, thus providing a structure in which the alarm-signal may be transmitted over one limb only of the line in case the opposite limb should become accidentally broken. The two windings of the electromagnet may be superimposed or may be twin windings or may be located upon opposite ends of the magnet-core, in which case they would be provided with non-inductive shunts or other well-known means for preventing their interference with the rapidly-alternating telephonic currents. The organization illustrated also comprises means by which any electromagnet, with its associated

local circuit apparatus; may be brought into association with any line of the telephone system in a systematic and workmanlike manner and without disturbing the permanent wiring.

The invention will be further illustrated and described in the accompanying drawings, in which—

Figure 1 is a diagram illustrating two subscribers' lines extending in a metallic circuit from the substations to a central-battery telephone-exchange switchboard of the two-wire type, with the connecting cord and accessory apparatus, the system being organized and equipped in accordance with the preferred forms of my invention. Fig. 2 illustrates a modification of the connections of the bridged impedance and the make-and-break mechanism. Figs. 3 and 4 illustrate my invention in its simpler form, in which the central battery is not grounded at its center and in which the resistance of the bridged impedance is the same for each side of the circuit in a switchboard system of the three-wire type. Fig. 5 illustrates well-known cord connecting apparatus for association with the line-circuit of Figs. 3 and 4. Fig. 6 indicates means for associating the special electromagnet with any telephone-line of the system without disturbing the permanent exchange-wiring.

Like characters refer to like parts in the several drawings.

Referring to Fig. 1, the subscribers' stations A and B are provided with the usual apparatus, adapted, preferably, for use with a central source of current-supply and comprising a receiver *r* and transmitter *t* in a circuit which normally stands open at the hook-switch *h*, the bell *b* and condenser *c* being in permanent bridge of the line. While I have thus illustrated one particular form of station arrangement, it will be apparent to those skilled in the art that numerous other arrangements may be equally well employed in my invention, and I therefore do not wish to be limited to the particular one shown. The limbs 1 and 2 of the line extend to the central office and are there connected, limb 1 through armature 6 and contact 9 of the cut-off relay 3 and the winding of relay 4 to the negative side of the battery *C*, and limb 2 through armature 7 and contact 8 of the cut-off relay, and resistance 11 to the positive side of the same battery. While I have here shown the connection of resistance 11, it will be understood from the following description that this resistance is only used in such lines as have alarm equipments, the other lines being directly connected from contact 8 to the positive pole of the battery. The subscriber in calling raises his receiver and completes the low-resistance circuit, including his transmitter and hook-switch contact, to actuate the relay 4, lighting his line-lamp 5. Upon

the insertion of an answering-plug in the operation of relay 3 breaks the normal connection of the line-limbs through relay 4 and resistance 11 to the battery *C*, thus extinguishing the line-lamp and connects them to the spring-jacks 10 and thence to strands 16 and 18 of the cord-circuit. Current is now supplied to the line A from battery *C* through relays 12 and 14, which control the circuit of the supervisory lamp 20, the lamp remaining dark as long as current flows through relay 12. The operator tests, plugs in, and rings a wanted subscriber in the usual way with calling-plug *O* and ringing-key *g*. While ringing, the relay 3 is energized by current from battery *E* and generator *G*, and after the ringing-key is released relay 15 of the cord-circuit and relay 3 of line B are energized by current from battery *D*. The relay 15 when thus actuated cuts off the test-relay 22 and completes the circuit of strand 17 through its contacts and also completes the circuit of supervisory lamp 21. When the called subscriber answers, current is furnished his instrument through relays 15 and 13, and the energization of relay 13 opens the circuit of lamp 21, causing its effacement as long as the subscriber's hook-switch contact remains closed. The subscribers are now able to converse over cord-strands 16 17 and 18 19, which include the condensers *dd* of the cord-circuit. The hanging up of both receivers deprives the relays 12 and 13 of current, thus allowing them to complete the circuits of lamps 20 and 21, which being illuminated constitute the disconnect-signal. This is the regular telephonic operation of the system and is not interfered with by the presence of the alarm apparatus associated with any of the lines. Those lines which are to be utilized for alarm service are provided with a magnet *F*, having two energizing-windings (one for each limb of the line, respectively) of equal energizing capacity and connected differentially or in such a manner that the energizing effect of the telephonic currents will be opposed in the two windings. These windings, as will be understood by those skilled in the art, may be "twin" or parallel windings or may be superimposed or "concentric" windings and will in either case present no objectionable impedance to the telephonic currents. This magnet, as will be hereinafter explained, controls mechanism for causing an alarm or other signal at the alarm-receiving station. At the alarm-sending station or other convenient point an impedance *I* is provided in bridge of the two-line limbs, having its center point connected to earth, as indicated, and this bridged connection also includes the non-inductive resistance *i*. It is to be understood that in the organization of this figure this bridged impedance is to be arranged in any suitable manner by which the inductance from either limb to ground

shall be substantially equal, while the ohmic resistance between either limb and ground is to be substantially different. The impedance I and resistance i are therefore only conventional illustrations of such an arrangement, and I do not limit myself to any specific structure for this bridge. Alarm-sending apparatus M is provided at a point intermediate of the impedance-bridge and the magnet F , which may be of the character of the well-known district messenger-box or similar apparatus, arranged to be released manually or automatically, and this mechanism controls, by its contacts, the circuit of the two-line limbs. In the conventional illustration of the drawings the make-and-break wheel n is normally prevented from revolving through the engagement of stop 24 with releasing-arm 26, the said arm being held in its position through the attraction of magnet 25, which is included in the circuit of battery 23, together with the thermostatic or other circuit-breaking devices (indicated at f). In case an alarm is to be given the opening of this circuit, as indicated at f' , in connection with line B causes the deenergization of magnet 25, allowing the arm 26 to be retracted by its associated spring, disengaging stop 24 and allowing the revolution of the make-and-break wheel n . As this wheel revolves the projections upon its periphery will cause limbs 1 and 2 to be interrupted at contacts 27 in accordance with a predetermined code, as will be well understood by those skilled in the art. This portion of the structure is shown in its normal position at line A, while at line B it is shown in operation. The batteries C or D being grounded at their central point, the operation of the system is as follows: Under the normal condition of disuse of the telephone apparatus the circuit of battery C is closed through the line-limbs and the bridged impedance indicated at I , and were this impedance-bridge of equal ohmic resistance in its two halves the current in limbs 1 and 2 would be substantially equal and the magnet F would be unenergized. It is to be understood in this connection that the resistance 11 is substantially the same as that of relay 4 and that the ohmic resistance of the two line-limbs themselves is substantially equal. Upon the insertion of a plug, the line being then supplied with current through relays 12 14 or relays 13 15, which are of equal resistance in either case, the conditions would be the same, and they would not be altered by the completion of the circuit through the subscriber's instrument either before or after the insertion of a plug. Inasmuch, however, as that half of the impedance-bridge associated with limb 2 includes additional resistance, as indicated at i , the current in this limb of the line will be of lesser value than that in limb 1, and the magnet F will therefore be energized to an extent proportionate to the preponderance of current in limb 1. This limited energization, as I have shown, will be maintained either before or after the insertion of a connecting-plug and regardless of whether the substation-telephone is or is not in use. Being thus energized, the magnet in the structure indicated completes, by its armature 31, a circuit of battery 30, which includes the movable contact-piece 32, normally held against stop 33 by spring 35 and the magnet 28 of the alarm-indicating device. H. While this indicating device is a conventional illustration of the ordinary telegraphic register, it is to be understood that other alarm-indicating devices may be used which are adapted to respond to the control of magnet F . In case an alarm-signal is to be given the actuation of the make-and-break mechanism interrupts the circuit of the line-limbs in the predetermined characteristic manner, depriving the relay F of all current at each interruption, which consequently opens and closes the local circuit in the manner required to give the alarm-signal. This operated condition is that indicated in the drawing of line B. The bridged impedance I being of relatively high resistance, it is to be noted that in case either limb becomes accidentally grounded such direct earth connection will cause a material increase in current-flow in the corresponding line-limb. This increased current will consequently energize the magnet F to a greater extent, causing it to still further attract its armature and complete a circuit which may be traced from battery 30, through armature 31, contact-piece 32, contact 34, and lamp 29, causing the illumination of the lamp, which constitutes a ground-signal. The circuit of magnet 28 being still maintained at contact-piece 32 and armature 31, no alarm indication is given at this time. As will be well understood the tension of contact-piece 32 may be adjusted by means of spring 35 or in any other well-known way, and likewise the lamp 29 may be replaced by various other signaling devices known to the art. It will also be observed that should limb 1 or 2 of the line become accidentally broken at any point current will still continue to flow over the line-limb remaining intact, energizing the relay F and causing its proper actuation to indicate either an alarm-signal or a ground-signal at the proper time. During the process of calling a subscriber the relay F is energized by current from battery E and generator G, a sufficient portion being diverted to ground through the impedance I to cause a preponderating effect in the winding associated with limb 1.

Fig. 2 indicates a modification of the circuit-breaking and substation arrangement of Fig. 1, the make-and-break device being indicated diagrammatically at M' . In this modification the impedance I may in itself or externally be provided with additional resist-

1
ance for limb 2—such, for example, as the bell *b*—included in circuit with the wire 31. In either case it is to be understood that the inductance associated with each line-limb is substantially the same, while the ohmic resistance between limb 2 and ground is substantially greater than that between limb 1 and ground. In this modification the line-limbs instead of being carried through the contacts of the make-and-break device are continuous, and the make-and-break device is included in the ground branch, as indicated by contact-brush 36, resting upon the uninsulated portion of wheel 37, which is connected to ground. As in the case of Fig. 1, the normal current-flow will be greater through limb 1 than through limb 2. When, however, the alarm-sending apparatus is released, as indicated by the revolution of wheel 37, the ground branch from the impedance-bridge is broken as each insulated segment of the wheel 37 passes under brush 36. At each interruption of this ground branch the current in both line-limbs becomes substantially the same, and the magnet *F* is consequently deenergized, thus causing the operation of the alarm-indicating device in the manner previously described. The modification of Fig. 2 differs, therefore, from the structure of Fig. 1 in that the magnet *F* is actuated through the removal of the preponderating current in one of its windings rather than through the subtraction of current from both windings.

In Figs. 3, 4, and 5 are indicated modifications of my invention as embodied in a well-known telephone-exchange system of what is known as the "three-wire" type. This system differs from that of the previous drawings in that the cut-off relay 3, associated with one limb of the talking-circuit, is replaced by a cut-off relay 41, which is included in a strictly local circuit having separate spring-jack terminals 40 and corresponding plug-terminals 44. In its telephonic operation the subscriber calls in the usual manner by removing his receiver from its hook-switch, thus completing a circuit of battery *C*, through line-relay 4, the contacts of the cut-off relay 41, the line-limbs and the substation instrument, thus energizing relay 4 and lighting the telephone-line lamp 5. When the operator inserts a plug, the circuit from the cut-off relay is completed from the battery *C*, through resistance 48, lamp 20, plug and jack contacts 44 40, through the winding of relay 41 to the return side of the battery, thus energizing the relay and under normal conditions causing the lamp 20 to light. Through the insertion of a plug the current of battery *C* is now furnished to the line through the windings 71 and 72 of repeating-coil *J*, cord-strands 16 and 18, and plug-contacts 42 and 43, which engage corresponding contact-pieces of the jacks 39, and the subscriber being at his telephone the relay 45, which is included in strand 18, is en-

ergized, and by its contact completes a circuit in shunt of lamp 20, which includes the resistance 47, and causes the extinguishment of the lamp. The operator listens, tests, and rings in the well-known manner, and by plugging in completes a similar circuit for the subscriber who is to be called, which includes the windings 73 and 74 of the repeating-coil. The subscribers' circuits are thus inductively united for conversation by means of the repeating-coil rather than by condensers, as in the system of Fig. 1. Either subscriber can cause the illumination of his supervisory lamp 20 or 21 by actuating his hook-switch, thus energizing or deenergizing the relay 45 or 46, and the illumination of both lamps constitutes the customary disconnect-signal. The manipulations of the operator and subscriber and the action of the signals governed thereby are thus seen to be the same as in the system previously illustrated. With reference to the alarm apparatus it is to be noted that the batteries *C* are indicated as grounded at their positive terminals and that the impedance *I* is indicated as having substantially the same resistance between each line-limb and ground. Also that the make-and-break device indicated at *M* is only adapted to open the circuit of line-limb 1, the opposite limb being permanently continuous. Referring to Fig. 3, it will be seen that during the use of the telephone relay *F'*, which has its windings arranged similarly to the relay *F* of Fig. 1, is energized by current from battery *C* through relay 4, limb 1, device *M*, and impedance *I'* to ground, and that during the use of the telephone, while a circuit of decreased resistance is completed through both relay-windings the energization of relay *F'* still depends upon the preponderance of current through the circuit of limb 1, which includes the ground at *I'*. Upon the insertion of the connecting-plug, current now being furnished to the line through the substantially equal windings of the repeating-coil *J*, the conditions of current-flow through relay *F'* remain the same, it being understood that the relays 45 or 46 may be made of sufficiently low resistance to produce no objectionable unbalancing effect in the circuit. It will also be seen that when calling a subscriber the relay *F'* will be energized by current from the generator *G* flowing to ground at impedance *I*. If under any of the conditions stated the alarm-sending mechanism (indicated at *M*) be actuated, the consequent opening of limb 1 through the passage of the insulated segments of wheel 37 under contact-piece 36 will cause the actuation of relay *F'*, thus controlling the circuit of battery 30 to cause an alarm indication.

The modification of Fig. 4 differs from that of Fig. 3 only in that the windings of the relay *F'*, corresponding to relay *F*, are arranged upon opposite ends of the magnet-

core rather than being parallel or concentric wound, as indicated in Fig. 3. The windings of relay F^2 are arranged to present no objectionable impedance to the telephonic currents either by the non-inductive shunts (indicated at 38) or in any other well-known manner. While the structures of Figs. 3 and 4 do not show the ground-signal arrangement of Fig. 1 and do not indicate an arrangement by which the alarm service may be maintained by means of either line-limb in case its mate should become accidentally broken and do not indicate the substitution of the modification of Fig. 2 for that shown, these arrangements have been omitted from the drawings of the three-wire system for the sake of simplicity only. As will be understood from this description by those skilled in the art, the entire alarm-service arrangement of Fig. 1 may be equally well embodied in the "three-wire" system of Figs. 3, 4, and 5.

Fig. 6 indicates means by which any line of a telephone-exchange system may be provided with the special-alarm apparatus. The two limbs of the line enter the exchange, terminate in the customary manner upon the distributing-rack K at terminal 49, and are ordinarily carried through this rack by jumper-wires (indicated at 51 and 52) to terminals 50, and thence by permanently-connected wires to the other apparatus of the switchboard system. The energizing-windings of the special relay F or F' are permanently wired to terminals 57 of the same or an adjacent section of the distributing-rack and are provided with the customary protective devices, (indicated at 58.) In case it is desired to associate this relay and its controlled apparatus with any particular line the flexible jumper-wires are removed and connection is made by the two pairs of jumpers, as indicated at 53 54 and 55 56. In case it were desired to shift the magnet and its associated mechanism to some other line it would only be necessary to disconnect these removable jumpers from terminals 49 and 50 and transfer them to the corresponding terminals of the line to which the apparatus is to be shifted, removing its jumpers 51 and 52, as previously described. It will thus be understood by those skilled in the art that this arrangement provides means whereby any set of alarm-receiving mechanism may be interchangeably connected with any telephone-line circuit of the system in a neat and workmanlike manner and without disturbing any of the permanent wiring. To recapitulate, my invention contemplates a structure in which means may be provided for any line of a telephone-exchange system whereby a continuous current is maintained in the line of unequal value in the two-line limbs. Alarm-sending mechanism is associated with the line whereby this current

may be interrupted or intermittently made of equal value in both limbs in a predetermined manner. Alarm-receiving mechanism is associated with the line which will respond to such interruptions or changes in value of this normal current in a manner to give an alarm-signal, and this alarm-receiving mechanism may be arranged to give a ground-signal in response to an increased flow of current over one-line limb through its direct connection to earth.

While several batteries C, D, and E are shown in the drawings, it will be understood that these may be one and the same battery, and also that the various grounds indicated are or may be replaced by a common return-wire connected with the grounded terminal of the central battery.

It will also be understood that in the structures of the various drawings the bridged resistance or impedance I is sufficiently high to prevent a normal current-flow which would interfere with the telephonic operation of the line-relay 4 or the supervisory relays in the cord-circuits.

It will also be evident to those skilled in the art that many modifications of this system may be made without departing from the spirit of my invention, and I therefore do not wish to be limited to the precise structures shown and described; but

I claim—

1. In a telephone-exchange system, the combination of a line-circuit extending from a substation to the exchange, means for normally maintaining a current in the circuit of unequal value for the two limbs and means for interrupting said current in a predetermined manner and signal-controlling mechanism responsive to such interruptions.

2. In a telephone-exchange system, the combination of a line-circuit extending from a substation to the exchange, means for normally maintaining a current in the circuit of unequal value for the two limbs and alarm-sending mechanism for interrupting said current in a predetermined manner and alarm-receiving mechanism responsive to such interruptions.

3. In a telephone-exchange system, the combination of a line-circuit extending from a substation to the exchange, means for normally maintaining a current in the circuit of unequal value for the two limbs and means for changing the normal current to one of equal value for the two line-limbs and signal-controlling mechanism responsive to such change in value.

4. In a telephone-exchange system, the combination of a line-circuit extending from a substation to the exchange, means for normally maintaining a current in the circuit of unequal value for the two limbs and alarm-sending mechanism for changing the normal current to one of equal value for the two line-

limbs and alarm-receiving mechanism responsive to such change in value.

5. In a telephone-exchange system, the combination of a line-circuit extending from a substation to the exchange, means for normally maintaining a current in the circuit of unequal value for the two limbs and means for intermittently changing the normal current to one of equal value for the two line- 70 limbs and signal-controlling mechanism responsive to such changes in value.

6. In a telephone-exchange system, the combination of a line-circuit extending from a substation to the exchange, means for normally maintaining a current in the circuit of unequal value for the two limbs and alarm- 75 sending mechanism for intermittently changing the normal current to one of equal value for the two limbs and alarm-receiving mechanism responsive to such changes in value.

7. In a telephone-exchange system, the combination of a line-circuit extending from a substation to the exchange, a source of current for the line, a resistance in bridge of the 80 line connected to said source of current from an intermediate point by a third conductor, an electromagnet associated with the line adapted to be normally energized by a preponderance of current in one line-limb, means for interrupting the circuit of said source in a predetermined manner and mechanism controlled by the electromagnet for causing an alarm indication.

8. In a telephone-exchange system, the combination of a line-circuit extending from a substation to the exchange, a source of current for the line, a resistance in bridge of the line connected to said source of current from an intermediate point by a third conductor, 90 an electromagnet associated with the line adapted to be normally energized by a preponderance of current in one line-limb, means for interrupting the circuit of the line-limbs in a predetermined manner and mechanism controlled by the electromagnet for causing an alarm indication.

9. In a telephone-exchange system, the combination of a line-circuit extending from a substation to the exchange, a source of current for the line, a resistance in bridge of the line connected to said source of current from an intermediate point by a third conductor, an electromagnet associated with the line adapted to be normally energized by a pre- 100 ponderance of current in one line-limb, means for interrupting the circuit of said third conductor in a predetermined manner and mechanism controlled by the electromagnet for causing an alarm indication.

10. In a telephone-exchange system, the combination of a line-circuit extending from a substation to the exchange, a source of current for the line, a resistance in bridge of the line connected to said source of current from an intermediate point by a third conductor,

an electromagnet associated with the line adapted to be normally energized by a preponderance of current in one line-limb, means for interrupting the circuit of said resistance and third conductor in a predetermined manner and mechanism controlled by the electromagnet for causing an alarm indication. 70

11. In a telephone-exchange system, the combination of a line-circuit extending from a substation to the exchange, a source of current for the line, a resistance in bridge of the line connected to said source of current from an intermediate point by a third conductor, an electromagnet associated with the line adapted to be normally energized by current in one line-limb only, means for interrupting the circuit of said source in a predetermined manner and mechanism controlled by the electromagnet for causing an alarm indica- 80 tion.

12. In a telephone-exchange system, the combination of a line-circuit extending from a substation to the exchange, a source of current for the line, a resistance in bridge of the line connected to said source of current from an intermediate point by a third conductor, an electromagnet associated with the line adapted to be normally energized by current in one line-limb only, means for interrupting the circuit of the line-limbs in a predetermined manner and mechanism controlled by the electromagnet for causing an alarm indica- 95 tion.

13. In a telephone-exchange system, the combination of a line-circuit extending from a substation to the exchange, a source of current for the line, a resistance in bridge of the line connected to said source of current from an intermediate point by a third conductor, an electromagnet associated with the line adapted to be normally energized by current in one line-limb only, means for interrupting the circuit of said third conductor in a predetermined manner and mechanism controlled by the electromagnet for causing an alarm indication. 100

14. In a telephone-exchange system, the combination of a line-circuit extending from a substation to the exchange, a source of current for the line, a resistance in bridge of the line connected to said source of current from an intermediate point by a third conductor, an electromagnet associated with the line adapted to be normally energized by current in one line-limb only, means for interrupting the circuit of said resistance and third conductor in a predetermined manner and mechanism controlled by the electromagnet for causing an alarm indication. 110

15. In a telephone-exchange system, the combination of a line-circuit extending from a substation to the exchange, a source of current for the line, a resistance in bridge of the line connected to said source of current from an intermediate point by a third conductor, 120

an electromagnet associated with the line normally energized by current in the circuit of said third conductor, means for interrupting the circuit of said source in a predetermined manner and mechanism controlled by the electromagnet for causing an alarm indication.

16. In a telephone-exchange system, the combination of a line-circuit extending from
10 a substation to the exchange, a source of current for the line, a resistance in bridge of the line connected to said source of current from an intermediate point by a third conductor, an electromagnet associated with the line
15 normally energized by current in the circuit of said third conductor, means for interrupting the circuit of the line-limbs in a predetermined manner and mechanism controlled by the electromagnet for causing an alarm indication.

17. In a telephone-exchange system, the combination of a line-circuit extending from a substation to the exchange, a source of current for the line, a resistance in bridge of the line connected to said source of current from an intermediate point by a third conductor, an electromagnet associated with the line normally energized by current in the circuit of said third conductor, means for interrupting the circuit of said third conductor in a predetermined manner and mechanism controlled by the electromagnet for causing an alarm indication.

18. In a telephone-exchange system, the
35 combination of a line-circuit extending from
a substation to the exchange, a source of cur-
rent for the line, a resistance in bridge of the
line connected to said source of current from
an intermediate point by a third conductor,
40 an electromagnet associated with the line
normally energized by current in the circuit
of said third conductor, means for interrupt-
ing the circuit of said resistance and third
conductor in a predetermined manner and
45 mechanism controlled by the electromagnet
for causing an alarm indication.

19. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor, means for interrupting the circuit of said source in a predetermined manner and mechanism controlled by the electromagnet for causing an alarm indication.

60 20. In a telephone-exchange system, the combination of a line-circuit extending from a substation to the exchange, a source of current for the line, a resistance in bridge of the line connected to said source of current from 65 an intermediate point by a third conductor,

an electromagnet associated with the line, normally energized to a limited extent by current in the circuit of said resistance and third conductor, means for interrupting the circuit of said source in a predetermined manner and mechanism controlled by the limited energization of the electromagnet for causing an alarm indication.

21. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor, means for interrupting the circuit of said source in a predetermined manner and mechanism controlled by the limited energization of the electromagnet for causing an alarm indication and controlled by the greater energization of the electromagnet for causing a separate indication. 75 80 85

22. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor, means for interrupting the circuit of the line-limbs in a predetermined manner and mechanism controlled by the electromagnet for causing an alarm indication. 90 95 100

23. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor, means for interrupting the circuit of the line-limbs in a predetermined manner and mechanism controlled by the limited energization of the electromagnet for causing an alarm indication. 105 110 115

24. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor, means for interrupting the circuit of the line-limbs in a predetermined manner and mechanism controlled by the limited energization of the electromagnet for causing an alarm indication and controlled 130

- by the greater energization of the electromagnet for causing a separate indication.
25. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor, means for interrupting the circuit of said third conductor in a predetermined manner and mechanism controlled by the electromagnet for causing an alarm indication.
26. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor, means for interrupting the circuit of said third conductor in a predetermined manner and mechanism controlled by the limited energization of the electromagnet for causing an alarm indication.
27. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor, means for interrupting the circuit of said third conductor in a predetermined manner and mechanism controlled by the limited energization of the electromagnet for causing an alarm indication and controlled by the greater energization of the electromagnet for causing a separate indication.
28. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor, means for interrupting the circuit of said resistance and third conductor in a predetermined manner, and mechanism controlled by the electromagnet for causing an alarm indication.
29. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor, means for interrupting the circuit of said resistance and third conductor in a predetermined manner and mechanism controlled by the limited energization of the electromagnet for causing an alarm indication.
30. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor, means for interrupting the circuit of said resistance and third conductor in a predetermined manner and mechanism controlled by the limited energization of the electromagnet for causing an alarm indication and controlled by the greater energization of the electromagnet for causing a separate indication.
31. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor and adapted to be energized to a greater extent through the direct connection of a line-limb through said third conductor, means for interrupting the circuit of said source in a predetermined manner and mechanism controlled by the electromagnet for causing an alarm indication.
32. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor and adapted to be energized to a greater extent through the direct connection of a line-limb through said third conductor, means for interrupting the circuit of said source in a predetermined manner and mechanism controlled by the limited energization of the electromagnet for causing an alarm indication.
33. In a telephone-exchange system, the combination of a line-circuit extending from a substation to the exchange, a source of cur-

- rent for the line, a resistance in bridge of the line connected to said source of current from an intermediate point by a third conductor, an electromagnet associated with the line normally energized to a limited extent by current in the circuit of said resistance and third conductor and adapted to be energized to a greater extent through the direct connection of a line-limb through said third conductor, means for interrupting the circuit of said source in a predetermined manner and mechanism controlled by the limited energization of the electromagnet for causing an alarm indication and controlled by the greater energization of the electromagnet for causing a separate indication.
34. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor and adapted to be energized to a greater extent through the direct connection of a line-limb through said third conductor, means for interrupting the circuit of the line-limbs in a predetermined manner and mechanism controlled by the electromagnet for causing an alarm indication.
35. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor and adapted to be energized to a greater extent through the direct connection of a line-limb through said third conductor, means for interrupting the circuit of the line-limbs in a predetermined manner and mechanism controlled by the limited energization of the electromagnet for causing an alarm indication.
36. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor and adapted to be energized to a greater extent through the direct connection of a line-limb through said third conductor, means for interrupting the circuit of the line-limbs in a predetermined manner and mechanism controlled by the limited energization of the electromagnet for causing a separate indication.
37. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor and adapted to be energized to a greater extent through the direct connection of a line-limb through said third conductor, means for interrupting the circuit of said third conductor in a predetermined manner and mechanism controlled by the electromagnet for causing an alarm indication.
38. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor and adapted to be energized to a greater extent through the direct connection of a line-limb through said third conductor, means for interrupting the circuit of said third conductor in a predetermined manner and mechanism controlled by the limited energization of the electromagnet for causing an alarm indication.
39. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor and adapted to be energized to a greater extent through the direct connection of a line-limb through said third conductor, means for interrupting the circuit of said third conductor in a predetermined manner and mechanism controlled by the limited energization of the electromagnet for causing an alarm indication and controlled by the greater energization of the electromagnet for causing a separate indication.
40. In a telephone-exchange system, the combination of a line-circuit extending from a substation to the exchange, a source of current for the line, a resistance in bridge of the line connected to said source of current from an intermediate point by a third conductor, an electromagnet associated with the line

normally energized to a limited extent by current in the circuit of said resistance and third conductor and adapted to be energized to a greater extent through the direct connection of a line-limb through said third conductor, means for interrupting the circuit of said resistance and third conductor in a predetermined manner and mechanism controlled by the electromagnet for causing an alarm indication.

41. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor and adapted to be energized to a greater extent through the direct connection of a line-limb through said third conductor, means for interrupting the circuit of said resistance and third conductor in a predetermined manner and mechanism controlled by the limited energization of the electromagnet for causing an alarm indication.

42. In a telephone-exchange system, the combination of a line-circuit extending from a substation to the exchange, a source of current for the line, a resistance in bridge of the line connected to said source of current from an intermediate point by a third conductor, an electromagnet associated with the line normally energized to a limited extent by current in the circuit of said resistance and third conductor and adapted to be energized to a greater extent through the direct connection of a line-limb through said third conductor, means for interrupting the circuit of said resistance and third conductor in a predetermined manner and mechanism controlled by the limited energization of the electromagnet for causing an alarm indication and controlled by the greater energization of the electromagnet for causing a separate indication.

43. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value, an electromagnet associated with the line adapted to be normally energized by a preponderance of current in one line-limb, means for interrupting the circuit of said source in a predetermined manner and mechanism controlled by the electromagnet for causing an alarm indication.

44. In a telephone-exchange system, the combination of a line-circuit extending from

a substation to the exchange, a source of current for the line, a third conductor connecting the line-limbs to said source of current, said connection being exterior to the exchange and including resistance for each line-limb of substantially unequal value, an electromagnet associated with the line adapted to be normally energized by a preponderance of current in one line-limb, means for interrupting the circuit of the line-limbs in a predetermined manner and mechanism controlled by the electromagnet for causing an alarm indication.

45. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value, an electromagnet associated with the line adapted to be normally energized by a preponderance of current in one line-limb, means for interrupting the circuit of said third conductor in a predetermined manner and mechanism controlled by the electromagnet for causing an alarm indication.

46. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value, an electromagnet associated with the line adapted to be normally energized by a preponderance of current in one line-limb, means for interrupting the circuit of said resistance and third conductor in a predetermined manner and mechanism controlled by the electromagnet for causing an alarm indication.

47. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value, an electromagnet associated with the line adapted to be normally energized by current in one line-limb only, means for interrupting the circuit of said source in a predetermined manner and mechanism controlled by the electromagnet for causing an alarm indication.

48. In a telephone-exchange system, the combination of a line-circuit extending from a substation to the exchange, a source of current for the line, a third conductor connecting the line-limbs to said source of current, said connection being exterior to the exchange and including resistance for each line-

limb of substantially unequal value, an electromagnet associated with the line adapted to be normally energized by current in one line-limb only, means for interrupting the circuit of the line-limbs in a predetermined manner and mechanism controlled by the electromagnet for causing an alarm indication.

49. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line adapted to be normally energized by current in one line-limb only, means for interrupting the circuit of said third conductor in a predetermined manner and mechanism controlled by the electromagnet for causing an alarm indication.

50. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line adapted to be normally energized by current in one line-limb only, means for interrupting the circuit of said resistance and third conductor in a predetermined manner and mechanism controlled by the electromagnet for causing an alarm indication.

51. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized by current in the circuit of said third conductor, means for interrupting the circuit of said source in a predetermined manner and mechanism controlled by the electromagnet for causing an alarm indication.

52. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized by current in the circuit of said third conductor, means for interrupting the circuit of the line-limbs in a predetermined

manner and mechanism controlled by the electromagnet for causing an alarm indication.

53. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized by current in the circuit of said third conductor, means for interrupting the circuit of said third conductor in a predetermined manner and mechanism controlled by the electromagnet for causing an alarm-indication.

54. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized by current in the circuit of said third conductor, means for interrupting the circuit of said resistance and third conductor in a predetermined manner and mechanism controlled by the electromagnet for causing an alarm indication.

55. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor, means for interrupting the circuit of said source in a predetermined manner and mechanism controlled by the electromagnet for causing an alarm indication.

56. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor, means for interrupting the circuit of said source in a predetermined manner and mechanism controlled by the limited energization of the electromagnet for causing an alarm indication.

57. In a telephone-exchange system, the

combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor, means for interrupting the circuit of said source in a predetermined manner and mechanism controlled by the limited energization of the electromagnet for causing an alarm indication and controlled by the greater energization of the electromagnet for causing a separate indication.

58. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor, means for interrupting the circuit of the line-limbs in a predetermined manner and mechanism controlled by the electromagnet for causing an alarm indication.

59. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor, means for interrupting the circuit of the line-limbs in a predetermined manner and mechanism controlled by the limited energization of the electromagnet for causing an alarm indication.

60. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor, means for interrupting the circuit of the line-limbs in a predetermined manner and mechanism controlled by the limited energization of the electromagnet for causing an alarm indication and controlled by the

50

55

60

greater energization of the electromagnet for 65 causing a separate indication.

causing a separate indication.

61. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor, means for interrupting the circuit of said third conductor in a predetermined manner and mechanism controlled by the electromagnet for causing an alarm indication.

62. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor, means for interrupting the circuit of said third conductor in a predetermined manner and mechanism controlled by the limited energization of the electromagnet for causing an alarm indication. 85 90 95

64. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor, means for interrupting the circuit of said resistance and

third conductor in a predetermined manner and mechanism controlled by the electromagnet for causing an alarm indication.

65. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor, means for interrupting the circuit of said resistance and third conductor in a predetermined manner and mechanism controlled by the limited energization of the electromagnet for causing an alarm indication.

66. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor, means for interrupting the circuit of said resistance and third conductor in a predetermined manner and mechanism controlled by the limited energization of the electromagnet for causing an alarm indication and controlled by the greater energization of the electromagnet for causing a separate indication.

67. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor and adapted to be energized to a greater extent through the direct connection of a line-limb through said third conductor, means for interrupting the circuit of said source in a predetermined manner and mechanism controlled by the electromagnet for causing an alarm indication.

68. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor and adapt-

ed to be energized to a greater extent through the direct connection of a line-limb through said third conductor, means for interrupting the circuit of said source in a predetermined manner and mechanism controlled by the limited energization of the electromagnet for causing an alarm indication.

69. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor and adapted to be energized to a greater extent through the direct connection of a line-limb through said third conductor, means for interrupting the circuit of said source in a predetermined manner and mechanism controlled by the limited energization of the electromagnet for causing an alarm indication and controlled by the greater energization of the electromagnet for causing a separate indication.

70. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor and adapted to be energized to a greater extent through the direct connection of a line-limb through said third conductor, means for interrupting the circuit of the line-limbs in a predetermined manner and mechanism controlled by the electromagnet for causing an alarm indication.

71. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor and adapted to be energized to a greater extent through the direct connection of a line-limb through said third conductor, means for interrupting the circuit of the line-limbs in a predetermined manner and mechanism controlled by the limited energization of the electromagnet for causing an alarm indication.

72. In a telephone-exchange system, the

combination of a line-circuit extending from a substation to the exchange, a source of current for the line, a third conductor connecting the line-limbs to said source of current 5 said connection being exterior to the exchange and including resistance for each line-limb of substantially unequal value, an electromagnet associated with the line normally energized to a limited extent by current in 10 the circuit of said resistance and third conductor and adapted to be energized to a greater extent through the direct connection of a line-limb through said third conductor, means for interrupting the circuit of the line 15 limbs in a predetermined manner and mechanism controlled by the limited energization of the electromagnet for causing an alarm indication and controlled by the greater energization of the electromagnet for causing a 20 separate indication.

20 separate indication.

73. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally 25 energized to a limited extent by current in the circuit of said resistance and third conductor and adapted to be energized to a greater extent through the direct connection of a line-limb through said third conductor, 30 means for interrupting the circuit of said third conductor in a predetermined manner and mechanism controlled by the electromagnet for causing an alarm indication.

35

net for causing an alarm indication.

74. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value, an electromagnet associated with the line normally energized to a limited extent by current in the circuit of said resistance and third conductor and adapted to be energized to a greater extent through the direct connection of a line-limb through said third conductor, means for interrupting the circuit of said third conductor in a predetermined manner and mechanism controlled by the limited energization of the electromagnet for causing an alarm indication.

65. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value, an elec-

tromagnet associated with the line normally energized to a limited extent by current in the circuit of said resistance and third conductor and adapted to be energized to a greater extent through the direct connection of a line-limb through said third conductor, means for interrupting the circuit of said third conductor in a predetermined manner and mechanism controlled by the limited energization of the electromagnet for causing an alarm indication and controlled by the greater energization of the electromagnet for causing a separate indication.

causing a separate indication.

76. In a telephone-exchange system, the combination of a line-circuit-extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor and adapted to be energized to a greater extent through the direct connection of a line-limb through said third conductor, means for interrupting the circuit of said resistance and third conductor in a predetermined manner and mechanism controlled by the electromagnet for causing an alarm indication.

77. In a telephone-exchange system, the combination of a line-circuit extending from a substation to the exchange, a source of current for the line, a third conductor connecting the line-limbs to said source of current said connection being exterior to the exchange and including resistance for each line-limb of substantially unequal value, an electromagnet associated with the line normally energized to a limited extent by current in the circuit of said resistance and third conductor and adapted to be energized to a greater extent through the direct connection of a line-limb through said third conductor, means for interrupting the circuit of said resistance and third conductor in a predetermined manner and mechanism controlled by the limited energization of the electromagnet for causing an alarm indication. 100 105 110 115

an alarm indication.

78. In a telephone-exchange system, the combination of a line-circuit extending from a substation to the exchange, a source of current for the line, a third conductor connecting the line-limbs to said source of current said connection being exterior to the exchange, and including resistance for each line-limb of substantially unequal value, an electromagnet associated with the line normally energized to a limited extent by current in the circuit of said resistance and third conductor and adapted to be energized to a greater extent through the direct connection of a line-limb through said third conductor, means for

interrupting the circuit of said resistance and third conductor in a predetermined manner and mechanism controlled by the limited energization of the electromagnet for causing 5 an alarm indication and controlled by the greater energization of the electromagnet for causing a separate indication.

79. In a telephone-exchange system, the combination of a line-circuit extending from 10 a substation to the exchange, a source of current for the line, a third conductor connecting the line-limbs to said source of current, said connection being exterior to the exchange and including resistance for each line-limb of 15 substantially unequal value but of substantially equal impedance to variable currents, an electromagnet associated with the line adapted to be normally energized by a preponderance of current in one line-limb, means 20 for interrupting the circuit of said source in a predetermined manner and mechanism controlled by the electromagnet for causing an alarm indication.

80. In a telephone-exchange system, the combination of a line-circuit extending from 25 a substation to the exchange, a source of current for the line, a third conductor connecting the line-limbs to said source of current, said connection being exterior to the exchange 30 and including resistance for each line-limb of substantially unequal value but of substantially equal impedance to variable currents, an electromagnet associated with the line adapted to be normally energized by a pre- 35 ponderance of current in one line-limb, means for interrupting the circuit of the line-limbs in a predetermined manner and mechanism controlled by the electromagnet for causing an alarm indication.

40 81. In a telephone-exchange system, the combination of a line-circuit extending from a substation to the exchange, a source of current for the line, a third conductor connecting the line-limbs to said source of current, 45 said connection being exterior to the exchange and including resistance for each line-limb of substantially unequal value but of substantially equal impedance to variable currents, an electromagnet associated with the line 50 adapted to be normally energized by a preponderance of current in one line-limb, means for interrupting the circuit of said third conductor in a predetermined manner and mechanism controlled by the electromagnet for causing an alarm indication.

55 82. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents,

an electromagnet associated with the line 65 adapted to be normally energized by a preponderance of current in one line-limb, means for interrupting the circuit of said resistance and third conductor in a predetermined manner and mechanism controlled by the electromagnet for causing an alarm indication. 70

83. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, 75 an electromagnet associated with the line adapted to be normally energized by current in one line-limb only, means for interrupting the circuit of said source in a predetermined manner and mechanism controlled by the electromagnet for causing an alarm indication. 80

84. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line adapted to be normally energized by current in one line-limb only, means for interrupting the circuit of the line-limbs in a predetermined manner and mechanism controlled by the electromagnet for causing an alarm indication. 90

85. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line adapted to be normally energized by current in one line-limb only, means for interrupting the circuit of said third conductor in a predetermined manner and mechanism controlled by the electromagnet for causing an alarm indication. 100

86. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, 105 an electromagnet associated with the line 110

adapted to be normally energized by current in one line-limb only, means for interrupting the circuit of said resistance and third conductor in a predetermined manner and mechanism controlled by the electromagnet for causing an alarm indication.

87. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized by current in the circuit of said third conductor, means for interrupting the circuit of said source in a predetermined manner and mechanism controlled by the electromagnet for causing an alarm indication.

88. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized by current in the circuit of said third conductor, means for interrupting the circuit of the line-limbs in a predetermined manner, and mechanism controlled by the electromagnet for causing an alarm indication.

89. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized by current in the circuit of said third conductor, means for interrupting the circuit of said third conductor in a predetermined manner and mechanism controlled by the electromagnet for causing an alarm indication.

90. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but substantially equal impedance to variable currents, an electromagnet associated with the

line normally energized by current in the circuit of said third conductor, means for interrupting the circuit of said resistance and third conductor in a predetermined manner and mechanism controlled by the electromagnet for causing an alarm indication.

91. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor, means for interrupting the circuit of said source in a predetermined manner and mechanism controlled by the electromagnet for causing an alarm indication.

92. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor, means for interrupting the circuit of said source in a predetermined manner and mechanism controlled by the limited energization of the electromagnet for causing an alarm indication.

93. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor, means for interrupting the circuit of said source in a predetermined manner and mechanism controlled by the limited energization of the electromagnet for causing an alarm indication and controlled by the greater energization of the electromagnet for causing a separate indication.

94. In a telephone-exchange system, the combination of a line-circuit extending from a substation to the exchange, a source of current for the line, a third conductor connect-

ing the line-limbs to said source of current, said connection being exterior to the exchange and including resistance for each line-limb of substantially unequal value but of 5 substantially equal impedance to variable currents, an electromagnet associated with the line normally energized to a limited extent by current in the circuit of said resistance and third conductor, means for interrupting the circuit of the line-limbs in a predetermined manner and mechanism controlled by the electromagnet for causing an alarm indication.

95. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor, means for interrupting the circuit of the line-limbs in a predetermined manner and mechanism controlled by the limited energization of the electromagnet for causing an alarm indication.

96. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor, means for interrupting the circuit of the line-limbs in a predetermined manner and mechanism controlled by the limited energization of the electromagnet for causing an alarm indication and controlled by the greater energization of the electromagnet for causing a separate indication.

97. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor, means for interrupting the circuit of said third conductor in a predetermined manner and mechanism

controlled by the electromagnet for causing an alarm indication.

98. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor, means for interrupting the circuit of said third conductor in a predetermined manner and mechanism controlled by the limited energization of the electromagnet for causing an alarm indication.

99. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor, means for interrupting the circuit of said third conductor in a predetermined manner and mechanism controlled by the limited energization of the electromagnet for causing an alarm indication and controlled by the greater energization of the electromagnet for causing a separate indication.

100. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor, means for interrupting the circuit of said resistance and third conductor in a predetermined manner and mechanism controlled by the electromagnet for causing an alarm indication.

101. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of

substantially equal impedance to variable currents, an electromagnet associated with the line normally energized to a limited extent by current in the circuit of said resistance and third conductor, means for interrupting the circuit of said resistance and third conductor in a predetermined manner and mechanism controlled by the limited energization of the electromagnet for causing an alarm indication.

102. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor, means for interrupting the circuit of said resistance and third conductor in a predetermined manner and mechanism controlled by the limited energization of the electromagnet for causing an alarm indication and controlled by the greater energization of the electromagnet for causing a separate indication.

103. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor and adapted to be energized to a greater extent through the direct connection of a line-limb through said third conductor, means for interrupting the circuit of said source in a predetermined manner and mechanism controlled by the electromagnet for causing an alarm indication.

104. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor and adapted to be energized to a greater extent through the direct connection of a line-limb through said

third conductor, means for interrupting the circuit of said source in a predetermined manner and mechanism controlled by the limited energization of the electromagnet for causing an alarm indication.

105. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor and adapted to be energized to a greater extent through the direct connection of a line-limb through said third conductor, means for interrupting the circuit of said source in a predetermined manner and mechanism controlled by the limited energization of the electromagnet for causing an alarm indication and controlled by the greater energization of the electromagnet for causing a separate indication.

106. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor and adapted to be energized to a greater extent through the direct connection of a line-limb through said third conductor, means for interrupting the circuit of the line-limbs in a predetermined manner and mechanism controlled by the electromagnet for causing an alarm indication.

107. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor and adapted to be energized to a greater extent through the direct connection of a line-limb through said third conductor, means for interrupting the circuit of the line-limbs in a predetermined manner and mechanism controlled by the

limited energization of the electromagnet for causing an alarm indication.

108. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor and adapted to be energized to a greater extent through the direct connection of a line-limb through said third conductor, means for interrupting the circuit of the line-limbs in a predetermined manner and mechanism controlled by the limited energization of the electromagnet for causing an alarm indication and controlled by the greater energization of the electromagnet for causing a separate indication.
109. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor and adapted to be energized to a greater extent through the direct connection of a line-limb through said third conductor, means for interrupting the circuit of said third conductor in a predetermined manner and mechanism controlled by the limited energization of the electromagnet for causing an alarm indication.
110. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor and adapted to be energized to a greater extent through the direct connection of a line-limb through said third conductor, means for interrupting the circuit of said third conductor in a predetermined manner and mechanism controlled by the limited energization of the electromagnet for causing an alarm indication.
111. In a telephone-exchange system, the

combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor and adapted to be energized to a greater extent through the direct connection of a line-limb through said third conductor, means for interrupting the circuit of said third conductor in a predetermined manner and mechanism controlled by the limited energization of the electromagnet for causing an alarm indication and controlled by the greater energization of the electromagnet for causing a separate indication.

112. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor and adapted to be energized to a greater extent through the direct connection of a line-limb through said third conductor, means for interrupting the circuit of said resistance and third conductor in a predetermined manner and mechanism controlled by the electromagnet for causing an alarm indication.

113. In a telephone-exchange system, the combination of a line-circuit extending from a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor and adapted to be energized to a greater extent through the direct connection of a line-limb through said third conductor, means for interrupting the circuit of said resistance and third conductor in a predetermined manner and mechanism controlled by the limited energization of the electromagnet for causing an alarm indication.

114. In a telephone-exchange system, the combination of a line-circuit extending from

- a substation to the exchange, a source of current for the line, a third conductor connecting the line-limbs to said source of current, said connection being exterior to the exchange and including resistance for each line-limb of substantially unequal value but of substantially equal impedance to variable currents, an electromagnet associated with the line normally energized to a limited extent by current in the circuit of said resistance and third conductor and adapted to be energized to a greater extent through the direct connection of a line-limb through said third conductor, means for interrupting the circuit of said resistance and third conductor in a predetermined manner and mechanism controlled by the limited energization of the electromagnet for causing an alarm indication and controlled by the greater energization of the electromagnet for causing a separate indication.
115. In a telephone-exchange system, the combination of a line-circuit extending from a substation to the exchange, means for normally maintaining a current in the circuit of unequal value for the two limbs, alarm-sending mechanism for intermittently interrupting the line-limbs and alarm-receiving mechanism responsive to such interruptions.
116. In a telephone-exchange system, the combination of a line-circuit extending from a substation to the exchange, a source of current for the line, a resistance in bridge of the line, connected to said source of current from an intermediate point by a third conductor, an electromagnet associated with the line normally energized by the normal preponderance of current in one line-limb, means for varying the ratio of the current values in the line-limbs in a predetermined manner to operate said electromagnet, and mechanism controlled by the electromagnet for causing an alarm indication.
117. In a telephone-exchange system, the combination of a line-circuit extending from a substation to the exchange, means for normally maintaining a current in the circuit of unequal value for the two limbs of said line-circuit, means for changing the relative values of the current in said limbs in a predetermined manner and signal-controlling mechanism responsive to such change.
118. In a telephone-exchange system, the combination of a line-circuit extending from a substation to the exchange, means for normally maintaining a current in said circuit of unequal value for the two line-limbs of said circuit, electromagnetic mechanism having an energizing-winding associated with each of said line-limbs, means for changing the relative values of the current in said windings in a predetermined manner, and means responsive to said predetermined changes to indicate an alarm and responsive to another change to indicate a special signal.

119. In a telephone-exchange system, the combination of a line-circuit extending from a substation to the exchange, means for normally maintaining a current in said circuit of unequal value for the two line-limbs of said circuit, electromagnetic mechanism having an energizing-winding associated with each of said line-limbs, means for interrupting the circuit through said windings and means responsive to said interruptions to indicate an alarm and to an increased current-flow in one of said windings to indicate a special signal.

120. In a telephone-exchange system, the combination of a line-circuit extending from a substation to the exchange, means for normally maintaining a current in said circuit of unequal value for the two line-limbs of said circuit, electromagnetic mechanism having an energizing-winding associated with each of said line-limbs, means responsive to a decrease in the ratio of the normal current values in said windings to display a signal and to an increase in said ratio to display another signal.

121. In a telephone-exchange system, the combination of a line-circuit extending from a substation to the exchange, means for normally maintaining a current in said circuit of unequal value for the two line-limbs of said circuit, an electromagnet having an energizing-winding associated with each of said line-limbs, means responsive to a decrease of the normal energization of said electromagnet to display a signal and to an increase of said normal energization to display another signal.

122. In a telephone-exchange system, the combination of a line-circuit extending from a substation to the exchange, means for normally maintaining a current in said circuit of unequal value for the two line-limbs of said circuit, an electromagnet having an energizing-winding associated with each of said line-limbs, an armature for said magnet normally held in an intermediate position by the normal energization of said magnet and movable to a second position in response to a greater energization of said magnet and to a third position in response to its deenergization, a local circuit closed by said armature in its intermediate position and a second circuit closed by said armature in its fully-attracted position, and means for varying the current in the line-circuit to cause said armature to assume its different operating positions.

123. In a telephone-exchange system, the combination of a line-circuit extending from a substation to the exchange, means for normally supplying current to said circuit, electromagnetic means normally energized by said normal current-supply, a signal controlled by said electromagnetic means, a call-signal at the substation adapted to be actuated by alternating current, means for supplying alternating current to said circuit to actuate said

- call-signal, and means for maintaining said electromagnetic means in its normally energized condition during the application of said alternating current.
- 5 124. In a telephone-exchange system, the combination of a line-circuit extending from a substation to the exchange, means for normally supplying current to said circuit, electromagnetic means normally energized by said normal current-supply, a signal controlled by said electromagnetic means, a call-bell at the substation, means for supplying ringing-current to said circuit to actuate said call-bell, and means for maintaining said electromagnetic means in its normally energized condition during the application of said ringing-current.
- 10 125. A telephone-exchange system comprising a telephone-line extending from a substation to the exchange, a cut-off relay for changing the normal connections of said
- line at the exchange, a link-circuit for establishing connection with said line, means for normally supplying current to a circuit including said line, electromagnetic means normally energized by said normal current-supply, a signal controlled by said electromagnetic means, a call-bell at the substation, means for supplying ringing-current over said line-circuit to actuate said call-bell, and means for maintaining said electromagnetic means in its normally energized condition and for maintaining said cut-off relay energized during the application of said ringing-current.
